ROBERT A. PONSELLE, OF NEW YORK, N. Y.

PORTABLE POLISHING DEVICE

Application filed June 3, 1927. Serial No. 197,339.

This invention relates to a portable motor device in which tools of different kinds may be mounted to be driven by the motor, so that the device provided with appropriate tools may be used for many purposes. For example, by mounting a suitable brush in the device, the latter may be used for polishing floors, a long handle being first attached to the device to afford means for moving it over the floor surface. When the device is used for polishing furniture, buffing silver articles and other purposes the necessary changes are made to adapt it for those particular uses. In general, the device may be said to comprise a light, high speed motor with a speed reduction mechanism and a tool mounting, the whole being constructed as a portable unit.

The object of the invention is to provide a device of this kind which is of rugged though inexpensive construction, light in weight, easily operated and arranged so that changing of the tools and handles is a simple operation.

For the sake of clearness, an embodiment of the invention will be illustrated and described as it would be employed for polishing floors, though it is to be understood that its utility is by no means limited to that particular use. Such an embodiment includes a frame plate on which are mounted the motor, speed reduction connections, and a shaft serving as a tool mounting. This shaft has at least one free end for convenience in changing tools, the latter being slipped over the free end of the shaft and held in place in any convenient manner. This shaft is preferably supported in the desired position in the frame by means of a pair of plates or arms carried by the frame and spaced apart a short distance. The plates are preferably provided with bearings in which the shaft rotates although any other suitable means may be provided for mounting the shaft in the plates.

The motor is mounted on the frame at any convenient point with its axis parallel to the axis of rotation of the shaft, and is of the high speed type, so that it may be of light weight. The motor drives the tool through

reduction connections so that the tool may have the desired lower rate of speed, these connections including a belt which has a driving connection with the tool at one end thereof. In the event that a rotatable shaft is used, the tool may be rigidly connected to the shaft, as by means of a spline, and the shaft may carry a pulley over which runs a belt forming part of the driving connections.

When the device is used for polishing floors, a long handle is attached to it by means of a suitable handle bracket on the frame, and the motor leads are carried by the handle and led to a switch by which the motor can be controlled. When the device is used for polishing furniture, a handle of the same general type may be employed, so that the device can be conveniently moved about. The motor is carried on a mounting which automatically maintains the driving connections taut, thus overcoming the tendency of the belts to become slack due to stretching. The motor mounting is such that the motor can be readily removed so that it may be used to drive other machines, and the driving connections include a member driven from the shaft of the motor, but releasable therefrom when the motor is removed from its mounting. This member is maintained in operative position at all times by suitable means, so that after the motor is removed it may readily be attached without difficulty, and when remounted the driving connection between the motor shaft and this member is reestablished by the reattaching operation.

The device includes various other features of novelty, which will be apparent from a consideration of the accompanying drawings, in which

Fig. 1 is a view of the machine in side elevation and in operative position,

Fig. 2 is a front view of the machine as shown in Fig. 1,

Fig. 3 is a sectional view on an enlarged scale on the line 3—3 of Fig. 1, with the handle and its supporting bracket removed,

Fig. 4 is a sectional view on the line 4—4 of Fig. 3,

Fig. 5 and Fig. 6 are sectional views on the line 5—5 of Fig. 3, the views differing in

that certain parts are in different relative position,

Fig. 7 is a view of a detail of the mechanism, and

5 Fig. 8 is a sectional view on the line 8—8 of Fig. 3.

Referring now to these drawings, the machine is illustrated as consisting of a frame member or plate 10 carrying a motor 11, a 10 tool 12, and a handle 13, the tool being illustrated in the form of a cylindrical brush and the tool motor and handle lying in alignment. The handle is mounted detachably on the frame member by being secured by 15 a bolt with a wing nut 14 to a bracket 15 secured to the frame plate 10 at one end thereof.

The plate 10 has a circumferential flange 16 and is provided at each side of one end 20 thereof with brackets 17 in which are mounted rods 18 enclosed within sleeves. These rods project beyond the brackets in both directions and lie parallel. At one side of the bracket 17, each rod carries a short sleeve 25 19 and a plate 20 is mounted on the rods at the ends of the sleeves 19. Each rod likewise carries another sleeve 21 in contact with one face of the plate 20 and mounted on the rods beyond the sleeves 21 is another plate 30 22 held in place by screws which enter the ends of the rods. The plates 20 and 22 are provided with ball bearing assemblies generally designated 23, the inner members 24 of the ball bearing assemblies being mounted on a shaft 25 which has a free end 26 terminating adjacent the free ends of the rods 18.

The shaft 25 is the driving shaft for the tool, here illustrated as the cylindrical brush 40 12, this brush having a bore through its hub to receive the shaft 25 and being provided with a slot 27 into which fits a spline 28 on the shaft. The brush is held in position by means of a nut 29 on the free end of the shaft 45 so that with this arrangement the brush may be slipped over the free end of the shaft and held in position thereon by means of the nut, a driving connection between the brush and shaft being established by means of the 50 spline and slot. The brush is readily removable over the free end of the shaft by removal of the nut 29 and this permits the brush to be readily removed when occasion arises and likewise permits the substitution 55 of one form of tool for another, in accordance with the type of work to be performed.

Mounted on the shaft 25 between the plates 20 and 22 is a pulley 30 of any suitable construction secured to the shaft in any convenient manner, as by means of a set screw 31. This pulley is provided with face plates 32 between which runs a driving belt 33 and the pulley is spaced from the ball bearing assemblies in any convenient manner.

65 The driving motor 11, the casing of which

is provided with a handle 34, is mounted in place on a circular plate 35 having a circumferential flange 36 within which the end of the casing fits. This plate 35 is pivotally mounted on the plate member 10 by means of a stud 37 passing through an opening in the plate member and carrying a sleeve 38 at one end, the sleeve having an opening by means of which the stud may be lubricated. The plate 35 carries bosses 39 at diametrical 75 points in which are mounted shafts 40 which are provided with operating handles 41 and with pins 42 which enter slots 43 in the motor casing, so that when the shafts are in the position illustrated in Fig. 8, the pins enter the 80 slots and serve to anchor the motor rigidly in position. By swinging these shafts by means of the operating handles so that the pins 42 clear the slots 43, the motor may be readily removed by its handle 34.

The motor is provided with a square shaft 44 which passes through an opening in the mounting plate and through an elongated opening 44a in the frame plate in alignment therewith. The motor and its mounting plate are thus free to swing without the shaft coming into contact with the frame plate. Secured to the rear face of the motor mounting plate on suitable bosses 45 at either side of the opening through which the shaft extends, is a plate 46 which is spaced from the face of the mounting plate and is of generally U shape. Mounted between the legs of the U-plate 46 is a driving pulley 47 provided at one end with a circular hub 48 separated from the main part of the pulley by a circumferential channel 48a. The plate 46 straddles the pulley 47 and its legs enter the channel. The hub 48 is of larger diameter than the distance between the legs of the 100 plate 46 and the hub lies in the elongated slot in the main frame plate and close to the side wall thereof in such position that the pulley cannot be removed except by removal of the plate 46, once the parts are in assembled position. The pulley 47 has a square bore closely fitting the shaft 44 of the motor and carries a pair of leaf springs 49 which bear against opposite faces of the shaft when the motor is mounted in position, as illustrated 110 in Fig. 3.

With the arrangement described, it will be seen that by swinging the shafts 40 to free the pins 42 from the slots in the motor casing, the motor may readily be removed from the machine, but the pulley 47 remains substantially in alignment with the opening in the motor mounting plate at all times. When the motor is to be reattached to the mounting plate, its shaft is inserted through the square opening in the pulley 47 which has been held in position by means of the U-plate 46, the motor is then moved so that the end of its casing is in contact with the motor mounting plate and within the flange 36, and then the 120

handles 41 are swung to move the pins 42 into the slots in the motor casing.

Running on the pulley 47 is a belt 50 which passes around the large member of a compound pulley 51 mounted on a stud 52, the end of which is secured in a boss 53 on an arm 54 pivotally mounted on a stud 55 on the frame plate, the stud 52 passing through a slot 56 in the frame plate so that the arm 54 may be swung to a limited extent. The arm is acted upon by a spring 57 which tends to swing the arm in a direction away from the motor when the latter is mounted in position on the machine, and with this arrangement the spring 57 acts to maintain the belt 50 taut. The pulley is mounted on ball bearings conventionally illustrated at 58 on the stud 52 so that the pulley may run freely. On the smaller part of the compound pulley 51 runs the belt 33 which also passes over the pulley 30 on the drive shaft, the belt lying close to the rods 18 but between them.

With this construction, the tension of the spring 57 tends to swing the compound pulley 51 away from the pulley 30 so as to maintain the belt 33 taut at all times. The spring 57 likewise assists in maintaining the belt 50 taut because the motor mounting plate is swung on its pivot away from the compound pulley by means presently to be described.

The motor mounting plate is provided with a stud 59 which extends through an elongated slot 59' in the frame plate and has attached to it a spring 60 which is secured to a fixed part of the frame. This spring tends to swing the motor mounting in a direction away from the compound pulley 51. Attached to the same stud 59 is another spring 61 connected to a pin 62 mounted eccentrically on a disc 63 on the end of one of the shafts 40, the arrangement being such that the spring 61 tends to hold the shaft 40 with its pin 42 either in full engagement with the motor casing or entirely free therefrom. A similar spring 64 attached to the stud 59 is connected to a pin 65 eccentrically mounted on a disc 66 on the other shaft 40 and this disc is provided with an eccentrically mounted lug 67 of triangular shape. Mounted on a stud 68 on the frame plate is a segment 69 having teeth along one face, this segment being normally held against a stud 70 on the frame plate by means of a spring 71 attached to the free end of the segment and to a convenient part of the frame plate. The teeth of the segment are in position to contact with the triangular stud 67 as the handle 41 is moved, and when the handle is swung in a direction to free its pin from the motor casing, the stud 67 contacts with one of the teeth of the segment and upon further swinging of the handle 41, a wedging action results which tends to move the motor mounting plate in the direction toward the compound pulley 51. The spring 71 is much heavier

than the spring 60 so that the segment once engaged by the triangular stud, is moved to a very slight extent, while the motor mounting plate is moved to a considerable extent against the tension of spring 60.

The movement of the handle 41 which results in the swing of the motor plate is clearly illustrated in Figs. 5 and 6. In Fig. 5, the pins 42 are in engagement with the motor casing, and the motor is securely held in position with its shaft in driving engagement with the driving pulley 47. Upon swinging the handle 41 to the left in Figs. 5 and 6, so as to free its pin from the slot in the motor casing, the triangular lug 67 engages a tooth on the segment 69 as shown in Fig. 6, and as the handle is moved so that its pin is free of the slot the engagement of the stud and the segment causes the motor plate to be swung to the left. This releases the tension on the belt 50 so that the removal of the motor shaft from the driving pulley requires no considerable effort. When the motor is to be reattached its shaft is inserted into the square opening in the driving pulley and the handles 41 are then moved so that their pins enter the slots in the casing. This movement releases the triangular stud 67 from the teeth of the segment and the spring 60 draws the mounting plate in a direction away from the compound pulley 51 so as to make the belt 50 taut.

As previously mentioned, the pulley 47 is held in place by the U-shaped plate 46 so that upon removal of the motor, the pulley is not released from the frame plate. It is desirable to have the plate 46 fit loosely in the channel defining the hub 48, but a loose fit would give the pulley a considerable freedom of movement and make reinsertion of the shaft difficult. In order to overcome this difficulty, one of the shafts 40 has mounted thereon an arm 72 which carries a U-shaped plate 73 on the free end thereof. The arm has a channel 74 in its hub in which lies a pin 75 on the shaft 40 and the arrangement is such that when the shaft 40 is swung to release its pin 42 from the motor casing, its pin 75 engages the hub of the arm 72 after the shaft has made a part of its turning movement, and further movement of the shaft causes the arm to swing so that the legs of the plate 73 straddle the pulley 47 and lie in the channel therein at one side of the plate 46. The plate 73 and the plate 46 together serve to hold the pulley securely in position to be entered by the motor shaft when the motor is replaced. When the shaft 40 is moved to swing its pin 42 into engagement with the motor casing, the arm 72 is returned to normal position with the plate 73 free of the channel in the pulley 47. The arm 72 is connected to the shaft 40 by means of the slot and pin connection in order to give some freedom of movement between the two rotat-

ing parts, the shaft 40 requiring a greater arc of rotation to perform its function than does the arm 72. The arm carries an adjustable screw 76 which bears against the frame plate 10 to limit the movement of the shaft 40 when turned to cause its pin 42 to enter the slot of the motor casing and the other shaft 40 carries a similar pin which performs the same function in a similar manner.

10 Mounted between the plate 22 and a cross bar 77 connecting the free ends of the rods 18 is a curved plate 78 extending partly around the brush. This plate is held in place by means of studs 78' mounted in the plate 22 and cross bar, and is cut away to provide openings for the passage of belt 33. A flexible strip 79 is connected to one edge of the plate 78 and attached to the free end of this 15 flexible strip is a plate 80 which serves as a screen and normally lies in contact with the floor. The plate 80 prevents the brush from throwing dirt upwardly upon the machine when the latter is in operation, and the strip 20 acts as a swivel and permits the plate to contact with the floor regardless of irregularities therein, and regardless of the inclination of the device to the floor surface.

25 The motor is supplied with current by means of a cable 81 which leads to the motor terminals and extends upwardly along the handle 13 to a switch 82, a part of the cable (not shown) leading to any convenient outlet plug.

30 The driving connections are housed within a metal casing 83, the edge of which lies within the flange 16 on the frame plate, one end of the casing passing beneath a rearward extension on the plate 22 and bearing against the rods 18. Posts 84 extending outwardly from the frame plate support the casing and the latter is connected thereto by means of 35 screws.

40 It will be seen that the machine is of simple construction and of compact arrangement, it is easily operated and when used to polish floors, the entire weight of the machine may rest on the tool so that the latter is highly effective. The motor which is of the high speed type drives the tool at a reduced speed by means of the connections illustrated and these connections are arranged so that the belts are kept taut at all times. The belts ordinarily used in machines of this type are 45 subject to being stretched after a period of service, but in the present device any slackness in the belts is automatically taken up by the swinging of the motor mounting plate and of the arm 54 on which the intermediate 50 compound pulley is mounted. As the spring 55 57 is much heavier than any of the other springs on the machine, the motor mounting plate will be drawn away from the brush as the drive belt 33 becomes stretched, and for 60 that reason, the segment 69 is provided with

65 a series of teeth so that regardless of the position of the motor mounting plate, the triangular lug 67 will be in a position to engage a tooth on the segment when the shaft 40 is swung to permit the motor to be removed from the machine.

70 Since the machine is of relatively light weight and the handle can readily be removed, the machine may be used for many purposes besides cleaning floors.

75 I claim:

1. In a device of the type described, the combination of a frame, a rotary tool mounted thereon, a motor mounting on said frame, a motor adapted to be positioned in the mounting, means for removably securing the motor in the mounting so as to permit the complete removal of the motor therefrom and an indirect connection between the motor shaft and the tool including a member receiving the motor shaft to be driven thereby, and a support for holding the member substantially in operative position when the motor is removed from the mounting, whereby the replacement of the motor re-establishes the driving connection.

2. The combination of a frame, a rotary tool mounted in the frame, a motor mounting pivotally attached to the frame at one side of the tool and adapted to swing, a motor on said mounting, a shaft mounted in a pivoted support on the frame and carrying pulleys, the shaft mounting being arranged to swing, driving connections between the motor and one of said pulleys, and between the other pulley and the tool, and means tending to force the motor and shaft away from each other.

3. The combination of a frame, a tool mounted on the frame for rotation and adapted to contact with a surface to be operated on, a motor mounting movably attached to the frame, a motor detachably mounted on said mounting, a flexible driving connection between the motor and the tool, the mounting being provided with means tending to move the mounting to maintain the driving connection taut, and means for securing the motor to its mounting.

4. The combination of a frame, a motor pivotally and detachably mounted on said frame, a rotary tool mounted on the frame for rotation in contact with the surface to be operated on, a flexible driving connection between the motor and the tool, means for swinging the motor to maintain the driving connection taut, and means for locking the motor on its mounting, the said locking means being connected to the said means for swinging the motor to control the operation thereof.

5. The combination of a frame, a rotary tool mounted in the frame for rotation in contact with the surface to be operated on, a motor detachably mounted on the frame, a pulley adapted to receive the motor shaft

when the motor is in attached position, a driving connection between the pulley and the tool, and means for supporting the pulley in substantially normal operating position when the motor is removed from the machine and the shaft is disengaged from the pulley.

6. In a device of the type described, the combination of a frame, a rotary tool carried by the frame and adapted to rotate in contact with the surface to be operated upon, a motor mounting on the frame, a motor having a shaft, a second mounting on said frame, a pulley loosely supported by said second mounting, said pulley having a non-cylindrical opening therein adapted to receive a non-cylindrical extension on said motor shaft and to be supported thereby free of its mounting, a driving connection between the pulley and the tool, means for detachably securing the motor in its mounting, and means on the frame movable into engagement with the pulley to hold it against movement as the motor shaft is moved into and out of the pulley.

7. In a device of the type described, the combination of a frame, a tool thereon arranged for rotation in contact with the surface to be operated on, a plate pivotally mounted on the frame, a motor arranged for attachment to the plate, a flexible driving connection between the motor and the tool, means for swinging the plate to maintain the driving connection taut, means for holding the motor on its mounting, and means operable by the release of said holding means for swinging the mounting plate to slacken the said driving connection.

8. In a device of the type described, the combination of a frame, a tool mounted on the frame for rotation, a plate movably mounted on the frame, a motor detachably mounted on the plate, means acting on the plate and tending to force it toward the tool, a shaft carrying a compound pulley, a mounting for the shaft movably mounted on the frame, a belt leading from the motor shaft to the compound pulley and a second belt leading from the compound pulley to the tool, means acting on the shaft mounting to force the shaft away from the tool to maintain the belts taut, locking means for holding the motor on its mounting plate, and means operated by said locking means, when the latter is released, to move the motor mounting plate toward the shaft to slacken the belt between the motor and the compound pulley.

9. In a device of the type described, the combination of a frame, a tool mounted on the frame for rotation, a plate movably mounted on the frame, a motor detachably mounted on the plate, means acting on the plate and tending to force it toward the tool, a shaft carrying a compound pulley, a movable mounting on the plate for the shaft, a

belt leading from the motor shaft to the compound pulley, and a second belt leading from the compound pulley to the tool, means acting on the shaft mounting to force the shaft away from the tool to maintain the belts taut, locking means for holding the motor on its mounting plate, and means operative by the locking means when the latter is released to move the said plate to slacken the belt between the motor and the compound pulley, said moving means including a toothed segment attached to the frame and a stud attached to the motor mounting plate and engageable with the teeth of the segment.

10. The combination of a frame, a motor mounted on the frame, a rotary element adapted to receive the motor shaft to be driven thereby and supported thereon, and means on the frame independent of the shaft for engaging said element to position it in proper operative relation to the shaft lengthwise of the latter.

11. In a machine of the type described, the combination of a frame, a motor removably mounted on the frame, a rotary element carried loosely on the frame and adapted to be driven by the motor shaft, means attached to the frame for holding the motor in position thereon, means on the frame for engaging and positioning the rotary element in proper operative relation to the shaft lengthwise of the latter, and means when the motor is disconnected for maintaining the element in position to receive the shaft.

12. In a machine of the type described, the combination of a frame, a motor removably mounted on the frame, a rotary element on the frame having a non-cylindrical opening therein into which the motor shaft is insertable by a sliding motion, the shaft being formed to fit said opening so that the insertion of the shaft establishes a driving connection between it and the element, and a member on the frame independent of the shaft and movable into engagement with the element for positioning the latter in proper operative relation to the shaft.

13. In a device of the type described, the combination of a frame, a rotary element carried by the frame, a motor adapted to be mounted detachably on the frame and having a shaft receivable in said element to drive the latter, releasable means for securing the motor to the frame, and means operable by said securing means for positioning the element in operative position relative to the shaft lengthwise of the latter when the shaft is introduced into the element.

14. In a device of the type described, the combination of a frame, a rotary element carried by the frame, a motor adapted to be mounted detachably on the frame and having a shaft receivable in said element to drive the latter, releasable means for securing the motor to the frame, and a movable member

operative to engage the element and hold it against movement when the shaft is being introduced into and withdrawn therefrom.

15. In a device of the type described, the combination of a frame, a rotary element, a motor adapted to be mounted detachably on the frame, and having a shaft receivable in said element to support and drive the latter, releasable means for securing the motor to the frame, and a member on the frame movable to engage the element and hold it against movement with the shaft as the latter is inserted into and withdrawn from the element.

16. In a floor treating machine, a casing, a motor removably mounted on said casing so that the end of the shaft thereof extends within the casing, said end being non-cylindrical in form, a rotatable element within the casing having a non-cylindrical opening therein to receive said shaft, and spring clip means on said rotatable element engaging said shaft when its motor is mounted on the casing to hold said element in position thereon.

25 17. In a floor treating machine, a casing, a motor removably mounted on said casing so that the end of the shaft thereof extends within the casing, said end being non-cylindrical in form, a rotatable element within the 30 casing having a non-cylindrical opening therein to receive said shaft, and resilient clamping means on said element operated by mounting the motor on the casing to clamp said element in position on said shaft.

35 In testimony whereof I affix my signature.

ROBERT A. PONSELLE.
